(57) CLAIM

The ornamental design for a palo santo wood and sage holder, as shown and described.

DESCRIPTION

FIG. 1 is a front, top perspective view of a first embodiment of a palo santo wood and sage holder, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof.

FIG. 9 is a rear, bottom perspective view of a second embodiment of the palo santo wood and sage holder;

FIG. 10 is a rear, bottom perspective view of a third, embodiment of the palo santo wood and sage holder; and,

FIG. 11 is a rear, bottom perspective view of a fourth embodiment of the palo santo wood and sage holder.

The broken lines in the figures illustrate portions of the palo santo wood and sage holder that form no part of the claimed design.
